WILLIAM H. REIFF, OF PHILADELPHIA, PENNSYLVANIA.

Design No. 4,417, dated October 11, 1870.

DESIGN FOR A SHOW-CASE.

The Schedule referred to in these Letters Patent and making part of the same.

I, WILLIAM H. REIFF, of the city and county of Philadelphia and State of Pennsylvania, have invented and produced a new and original Design for "Show-Case," of which the following is a specification.

Figure 1 is a side view of my improved case, and Figure 2, a perspective view of part of the case.

The case A is rectangular, the top and bottom being parallel with each other, and the sides and ends inclined.

Claim.

A show case, having its top and bottom parallel and its front and sides or ends inclined, as shown and described.

WILLIAM H. REIFF.
